US00D535538S

(12) **United States Design Patent** (10) **Patent No.:** **US D535,538 S**
Sultan (45) **Date of Patent:** **** Jan. 23, 2007**

(54) **BLADE PROTECTOR WITH CAMOUFLAGE IMAGE FOR CHAIN SAW**

(75) Inventor: **Per Sultan**, Göteborg (SE)

(73) Assignee: **Aktiebolaget Electrolux**, Stockholm (SE)

(**) Term: **14 Years**

(21) Appl. No.: **29/216,486**

(22) Filed: **Nov. 3, 2004**

(30) **Foreign Application Priority Data**

May 4, 2004 (EM) 000174057

(51) **LOC (8) CI.** **08-05**

(52) **U.S. Cl.** **D8/70**

(58) **Field of Classification Search** D8/61-71, D8/85; D15/133, 138, 139, 140; 30/307, 30/347, 355, 388, 389-391, 381, 382, 383, 30/504, 151; 206/349; D3/220, 228, 254, D3/269
